UNITED STATES PATENT OFFICE.

SWAN N. TEVANDER, OF MAYWOOD, ILLINOIS, ASSIGNOR TO AMERICAN CAN COMPANY, OF NEW YORK, N. Y., A CORPORATION OF NEW JERSEY.

APPARATUS FOR AND PROCESS OF LINING CAN ENDS.

Application filed May 16, 1921. Serial No. 470,081.

This invention relates in general to the lining of can ends and has more particular reference to the provision of ends lined with compound applied in liquid or semi-liquid form.

5 The invention has for its principal object the application of the gasket liner material directly to the flange of the can end in minutely accurate measured amount and in such 10 fashion as to insure its even distribution over the area designed to receive it.

The invention has for a further object the provision of an apparatus and process of lining can ends, which will permit the accurate and satisfactory lining of the ends 15 with liner material thicker and less fluid than is readily practicable with the nozzle or jet apparatus now generally in use and well known to those skilled in the art.

20 Another highly important object of the invention is the provision for accurately measuring the entire charge and for varying the amount of this charge as conditions may render desirable.

25 Another important object of the invention is the provision of an apparatus and process insuring against the delivery of liner material except when a can end is present to receive it.

30 Numerous other objects and advantages of the invention will be apparent as it is better understood from the following description, which, taken in connection with the accompanying drawing, discloses a preferred 35 embodiment thereof.

Referring to the drawing,

Figure 1 is a top plan view, parts being shown in section, of an apparatus containing a preferred embodiment of the invention;

40 Fig. 2 is a section taken substantially on the line 2—2 of Fig. 1;

Fig. 3 is a detail section taken substantially on the line 3—3 of Fig. 4;

45 Fig. 4 is a section taken substantially on the line 4—4 of Fig. 1;

Fig. 5 is a section taken substantially on the line 5—5 of Fig. 4;

Fig. 6 is a section taken substantially on the line 6—6 of Fig. 5; and

50 Fig. 7 is a perspective view of one of the feeder disks.

The apparatus shown on the drawing for the purpose of illustrating the invention will be first described. Referring to Fig. 2, reference character 11 indicates the frame of

the machine and reference characters 12 and 13 brackets that extend up from it. These brackets support a reservoir comprising a body 14 having wings 15 and 16 resting upon and secured to the brackets 12 and 13. 60 The bottom of the reservoir consists of a plate 17 having an upwardly extending hollow sleeve 18 at its center which sleeve extends through a reservoir top plate 19. Within this sleeve is mounted a pressure plunger 65 21 having a head 22 adapted to engage the body of a can end as will be presently described. The plunger is provided with a stem 23 extending through a vertically adjustable bushing 24 and normally pushed 70 down by a spring 25 until a stop nut 26 engages the top of the bushing. The head of the plunger is rotatably mounted upon the stem, having a shoulder 27 engaged by the head 28 held in place in the stem by a screw 75 29. Antifriction balls 31 are provided to permit independent turning of the plunger head.

A can end support, consisting in the present instance of a seat member 32 upon the upper 80 end of a rod or stem 33, is arranged axially beneath the plunger head 22. A spring 34 is provided upon the lower end of this rod 33 and normally presses the can end support to the frame 11. Beneath the frame is 85 mounted a cross-shaft 35 in bearings 36 and upon this cross-shaft is a cam 37 adapted in the rotation of the shaft to lift the support and the can end carried by it into contact with the plunger head 22. Rotation is imparted to the can end by a bevel gear 38 90 mounted on shaft 35 and meshing with a bevel pinion 39 slidably embracing or keyed to the stem 33. The can ends to be lined are arranged in a magazine or stack holder 95 defined by posts 41 extending up from a plate 42, which plate is supported at 43 on the lower part of the bracket 13. Beneath this plate is arranged a reciprocating slide 44 having rollers 46 at one side movable 100 through a guide 45 carried on the frame. This slide is provided with a can end receiving recess 47 terminating in can end cut-out shoulders 48 at the rear end. The slide is reciprocated by a link 49 from any suitable 105 power source, being so timed with respect to the can end support or lift that it will deliver a can end thereto each time it returns to normal position after being lifted by the cam 37. 110

The slide carries fingers 51 at its forward end for pushing the can end previously positioned from the support, and these fingers move back with the slide beneath the support after it has been raised, as may be readily perceived on viewing Fig. 4.

The gasket material is fed to the rotating can ends in measured amounts, each charge in the present instance consisting of a number of measured drops or minute measured quantities. A number of disks 61, a sample of which is shown in Fig. 7, are provided. Each said disk is formed with several peripheral pockets 62. The plate or bottom 17 of the reservoir is given the general triangular shape shown in Fig. 5 and to each side or leg thereof a sector member 63 is fastened by bolts 64. Each sector member has a circular recess 65 in which a disk 61 is arranged and fitted, and this disk is mounted upon a rotatable pin or shaft 66 to which it is fixed against independent rotation by a tooth 67 engaging in the shaft. The walls of this recess close and make individual pockets 62 of the disk. This shaft has bearing in a sleeve 68 in the sector and in bearing 69 in the plate 17. A bevel pinion 71 is pinned to the outer end of each shaft 66 and these pinions are adapted to engage with a bevel gear ring 72 when the parts are assembled. This gear ring rests upon shoulders 73 upon the plate 17 and sectors 63, and in turn is surrounded by a second or actuating ring 74 held in place by an annulus 75 resting on the top of the gear ring and secured to the actuating ring by screws 76.

Referring now to Fig. 3, it will be noted that clutch recesses 77 are provided in the periphery of the gear ring and in these recesses are arranged clutch rollers 78 adapted to cause the gear ring 72 to move with the actuating ring 74 when the actuating ring is moved in a counterclockwise direction, viewing Fig. 3. The actuating ring is provided with an arm 81 having an extension 82 connected by a link 83 with a slide 84 movable in guides 85 alongside the slide 44. The slide 84 is in turn actuated by pivot arm 86 pivoted at 87 to the back of the slide 44 and having at its forward end a tooth 88 adapted for engagement in a recess 89 on the slide 84 when a can end is advanced by the slide 44. The tooth 88 normally rests out of position to engage the slide 84 and is moved into engaging position by a projection 91 on a lever 92 mounted upon the table or frame beneath the slide 44. This lever has a second projection 93 adapted to be engaged by the can end as it is advanced by the slide 44 and as will be readily appreciated upon examination of Fig. 1. The tooth 88 has an inclined face 94 at its rear side adapted to be engaged by a lug 95 on the slide return movement to

move the tooth back to normal position after the liner applying operation.

The operation of the apparatus and the practice of the process of my present invention will be readily apparent. The slide 44 is moved forward cutting out and advancing the lowermost can end from the magazine or stack between the posts 41. The presence of this can end moves the arm 86 down over into engagement with the slide 84 and further advance turns the actuating ring 74 on its idle stroke. As soon as the can end arrives on the support it is lifted into engagement with the plunger head 22 and against the disks 61 and at the same time is rotated by the gears 38 and 39. Upon the return stroke of the slide 44 the lug 88 engages the lug 95 of the slide 84 and moves the actuating ring in the opposite direction. This movement of the actuating ring produces like movement of the bevel gear ring 72 with corresponding rotation of the disks 61. These disks in rotating carry minute charges of liner material in the pockets 62, the material 96 between these pockets engaging curved end surfaces of the recesses in the sector plates 63 and serving as cut-offs, so that only measured quantities of material will be delivered and only by rotation of the disks. The disks operating together simultaneously deposit series of small measured quantities of the liner material on the flange of the can end and the surfaces between the pockets, rolling on the flange, distribute this material. The measuring is peculiarly accurate because of the small amounts delivered and it will be apparent that the disks rotating in the liner material itself can discharge semi-liquid as well as liquid if desired. The parts are preferably so arranged and timed that the material between pockets extends down to the can end flange and any excess rotation causes further spreading action. The amount deposited depends upon the arc of rotative movement given the gear 72 and I provide means for varying this rotative movement. Upon the arm extension 82 a number of points of attachment for the link 83 are provided, as indicated at 97. The link may thus be connected at any of these points of attachment and the angular throw correspondingly changed. I preferably also provide friction packing 98 between the gear ring 72 and the reservoir wall. A pipe 99 let into the side of the reservoir wall may be provided if desired to supply the liner material to the reservoir.

It is thought that the invention and many of its attendant advantages will be understood from the foregoing description, and it will be apparent that various changes may be made in the form, construction and arrangement of the parts without departing from the spirit and scope of the invention or sacrificing its material advantages, the

form hereinbefore being merely a preferred embodiment thereof.

I claim:

1. A method of applying a lining material to the flange of a can end, which comprises, delivering said lining material to said flange at distributed points of said flange simultaneously and spreading the same by a rolling action.
2. A method of applying a lining material to the flange of a can end, which comprises, delivering said lining material to said flange at distributed points of said flange simultaneously and in minute measured quantities and then spreading the same from such various points to form a continuous lining.
3. A method of applying a lining material to the flange of a can end, which comprises, delivering said lining material to said flange in a plurality of separated individually measured charges, the total of which is calculated to provide the desired lining material upon the flange.
4. A method of applying a lining material to the flange of a can end, which comprises, delivering said lining material to said flange substantially simultaneously at distributed points and in measured amount and then simultaneously rolling and distributing the material from said points to form a continuous lining.
5. A method of applying a lining material to the flange of a can end, which comprises, delivering said lining material to said flange progressively and simultaneously at distributed points in measured amount and then simultaneously rolling, pressing and spreading the quantities of material and thereby forming a continuous lining.
6. A method of applying a lining material to the flange of a can end, which comprises delivering lining material to the measuring chambers of a plurality of rotary feeding devices, and directly from said chambers to the flange of a can end, and distributing the material by the conjoint action of said feeding devices to form a continuous lining.
7. A method of applying a lining material to the flange of a can end, which comprises, delivering lining material to the measuring chambers of a rotary feeding device, and directly from said chambers to the flange of a can end, and rotating said rotary feeding device independently of the can end to distribute the material after its application to the can end and thereby forming a continuous lining from separately deposited quantities of said material.
8. An apparatus for applying lining material to the flange of a can end, comprising a support for the can end, a reservoir for said material, and a plurality of rotary liner material feeders arranged at spaced intervals and adapted to deliver material

substantially simultaneously to the flange of a can end on said support.

9. An apparatus for applying lining material to the flange of a can end, comprising a support for the can end, a reservoir for said material arranged centrally above said support, and a plurality of measuring liner material rotary feeders arranged at spaced intervals and adapted to deliver measured charges to the flange of a can end on said support.

10. An apparatus for applying lining material to the flange of a can end, comprising a rotary support for the can end, a reservoir for said material arranged centrally above said support, and liner material rotary feeders having a plurality of feeding chambers, all adapted to supply charges of liner material to the flange of a can end on said support and arranged around under said reservoir.

11. An apparatus for applying lining material to the flange of a can end, comprising a support for the can end, a reservoir for said material, means for rotating the can end, and liner material rotary feeders adapted to bear on said flange at various locations and depositing a plurality of separated charges of said material on the can end during its rotation.

12. An apparatus for applying lining material to the flange of a can end, comprising a support for the can end, a reservoir for said material, means for rotating the can end, and a liner material rotary feeder and recessed part wherein said feeder has a measuring function and deposits a plurality of individually measured charges of said material on the can end during its rotation, said feeder having recessed charge-holding portions and elevated pressing and distributing portions.

13. An apparatus for applying lining material to the flange of a can end, comprising a support for the can end, a reservoir for said material, and a rotary liner material feeder having a plurality of feeding chambers arranged around its periphery to come successively close to the surface of the can end flange, and rounded pressing elements between said chambers each depositing a measured charge on the flange of a can end on said support, and a recessed part wherein said feeder has a measuring function for said material.

14. An apparatus for applying lining material to the flange of a can end, comprising a rotating support for the can end, a reservoir for said material, a rotary liner material feeder having recesses around its periphery and depositing a plurality of spaced charges on the flange of a can end on said support, and means for controlling the extent of rotation of said feeder to control the

- amount of material supplied to said flange, and a recessed part wherein said rotary feeder has a measuring function. 15. An apparatus for applying lining material to the flange of a can end, comprising a rotating support for the can end, a liner material feeder, said liner material feeder having rounded projections and recesses around its periphery for depositing material on the flange of the can end and engaging the deposited material for spreading it over the flange, and a recessed part wherein said rotary feeder has a measuring function. 16. An apparatus for applying lining material to the flange of a can end, comprising a rotating support for the can end, a liner material feeder, said liner material feeder comprising a chambered wheel or disk and depositing liner material from said chambers to the flange of the can end by rolling therealong the parts of said wall between said chambers forming spreading means, and a recessed part wherein said rotary feeder has a measuring function. 17. An apparatus for applying lining material to the flange of a can end, comprising a magazine for containing can ends, a can end feeding device, and a plurality of lining material feeders adapted to deliver lining material to a plurality of predetermined points of said flange and to spread said deliveries to form a complete ring liner. 18. A method of applying a lining material to the flange of a can end, which comprises, delivering said lining material to said flange at a plurality of points simultaneously by means of a plurality of applying devices and spreading said deliveries by said devices to form a continuous flange lining. 19. A method of applying a lining material to the flange of a can end, which comprises, providing means for delivering said lining material to said flange at a plurality of spaced apart points simultaneously and flattening and spreading said lining material by said delivery means to form a complete can end flange liner. 20. The combination of rotary actuating means, rotary lining applying devices, turned by said actuating means, means for supplying lining material to said applying devices, rotary can end chucks for holding can ends within the sphere of operation of said applying devices, and mechanism for rotating said actuating means and said applying devices. 21. The combination of rotary actuating means, rotary lining applying devices turned by said actuating means, means for supplying lining material to said applying devices, rotary can end chucks for holding can ends within the sphere of operation of said applying devices, and mechanism for intermit-
- tently rotating said actuating means and said applying devices. 22. The combination of a reservoir, actuating means rotary around the same, rotary lining applying devices entering said reservoir and turned by said actuating means, rotary can end chucks for holding can ends within the sphere of operation of said applying devices, and mechanism for rotating said rotary means and said applying devices. 23. The combination of a rotary lining applying device, means for supplying lining material to said applying device, rotary can end chucks for holding can ends within the sphere of operation of said applying device, and mechanism independent of the can end for rotating said lining applying device. 24. The combination of a member having separable parts, rotary devices mounted between said separable parts and adapted to apply and cut off lining material to and from can ends, means for supplying lining material to said rotary devices, rotary can end chucks for holding can ends in the sphere of application of said rotary devices, and means for feeding can ends to said chucks. 25. The combination of a member having separable parts, a rotary device mounted between said separable parts and adapted to apply and cut off lining material to and from can ends, means for supplying lining material to said rotary device, rotary can end chucks for holding can ends in the sphere of application of said rotary device, and means for feeding can ends to said chucks. 26. The combination of a member having separable parts, a rotary device mounted between said separable parts and adapted to apply and cut off lining material to and from can ends, a reservoir entered by said rotary device for supplying lining material to the latter, rotary can end chuck for holding can ends in the sphere of application of said rotary device, and means for feeding can ends to said chucks. 27. The combination of a reservoir for lining material, a rotary device adapted to apply lining material from said reservoir to can ends and acting as a cut off of lining material from said reservoir, rotary can end chucks for holding can ends in the sphere of application of said rotary device, and means for feeding can ends to said chucks. 28. The combination of rotary can end chucks, means for feeding can ends thereto, a rotary device which controls the supply of lining material and applies the same to a can end in said chucks, and means for turning said rotary device which are operative by the aid of a can end about to be fed to said chucks by said feeding means.
